UNITED STATES PATENT OFFICE.

THEODORE WILLARD CASE, OF SCIPIO, NEW YORK.

APPARATUS FOR RECORDING LIGHT.

Application filed December 11, 1920. Serial No. 430,095.

To all whom it may concern:

Be it known that I, THEODORE W. CASE, of Scipio, in the county of Cayuga, in the State of New York, have invented new and useful Improvements in Apparatus for Recording Light, of which the following, taken in connection with the accompanying drawings, is a full, clear, and exact description.

This invention relates to certain improvements in apparatus for recording light.

The main object of the invention is the production of an apparatus that is capable of making a record of light, readable in known units, such as foot candles.

Another object is the production of a record sheet for use in connection with such an apparatus.

Another object is the utilization of variations in light to automatically control, through relays or other means, sources of artificial light, or means for excluding or admitting natural light, or for actuating a signal, etc.

Other objects and advantages relate to the details of construction and operation of the apparatus, all as will more fully appear from the following description, taken in connection with the drawings, in which:

Fig. 1 is a diagrammatic view of the electrical connections of an apparatus of my invention.

Fig. 2 is a diagrammatic view of the circuits of a constant speed motor for driving the mechanical parts of the apparatus.

Fig. 3 is an elevation of the recording mechanism.

Fig. 4 is a view of a portion of the apparatus of Fig. 3 in an unbalanced condition.

Fig. 5 is a sectional view of the pen and its parts.

Fig. 6 is an elevation of the sheet feeding mechanism.

Fig. 7 is a top plan view of the wheel that carries the slide wire.

Fig. 8 is a rear elevation of a portion of the recording mechanism illustrating the actuating means for the pen.

Fig. 9 is a view of a record sheet of my invention.

Fig. 10 is a diagrammatic illustration of a further use of the invention.

Generally speaking, the broad thought of the invention is the utilization of a light re-active device, such as a photo-electric

cell, or perhaps some other light re-active resistance for varying an electric current, such variations being in any suitable way translated into a record, which will correspond to the variations in the light reactive device, and may, therefore, be calibrated to indicate in known units the intensity of the rays to which the light reactive device is exposed.

When a pen or other record making instrument is used, its movement, or the movement of any other part of the recording mechanism may be utilized as a relay to transmit similar movement to other mechanism, or to actuate a device or devices controlling light producing or governing apparatus, to maintain, if desired, substantial uniformity of light intensity, or to actuate means controlling artificial light.

The record mechanism is generally the same as that used in the Leeds & Northrup temperature recorder, as for instance illustrated in Leeds Patent No. 1,125,699 dated January 19, 1915, and is fundamentally a self-balancing potentiometer. The potentiometer provides:

First: A means of securing known variable electromotive force; and

Second: Suitable electrical connections for bringing that electromotive force to a point where it may be balanced against the unknown electromotive force which results from variations in the resistance of the photo-electric cell dependent upon the intensity of the light rays to which the cell is exposed.

The two circuits are connected with opposite polarity, or so that the two E. M. F's oppose one another. Measurements are made with the potentiometer by varying a known electromotive force until it equals the unknown. When the two are equal, the index of the potentiometer—the galvanometer needle—stands motionless, and this needle is the controlling means of the recording apparatus.

Only a general description need be given of the L. & N. recorder. It consists of three distinct parts mounted together as one unit, (a) the measuring circuit, the potentiometer proper; (b) the motor and governor by which the mechanism is driven at constant speed; and (c) the automatic mechanism by which the potentiometer is kept balanced, and by which the measurements are recorded.

The potentiometer is of the split circuit

slide wire type. The battery —1—, which may consist of a few dry cells, supplies continuously flowing current to the potentiometer circuit, the current being maintained 5 constant by rheostat —2—. As the voltage in the battery —1— changes, the current in the potentiometer circuit will also change. To compensate for this change, a portion of the battery voltage is compared at intervals with the constant voltage of the standard cell —3—, and the rheostat —2— is adjusted until the proper current is flowing. This is accomplished by completing the circuit at —4—, which connects the galvanometer —5— in series with the standard cell across the resistance coil —6—. If the voltage across the coil is not equal to the voltage of the standard cell, the galvanometer will deflect from its zero position, in which 20 case the rheostat —2— should be adjusted until the galvanometer returns to its zero position. The two voltages are now equal and opposite, and the proper current is flowing.

25 A battery —7— of suitable electromotive force is connected in circuit across the electrodes —8— and —9— of the photo-electric cell. A variable resistance —10— is inserted in the circuit between the electrodes of 30 the photo-electric cell so that there is a drop in potential between the points —11— and —12—, causing a flow of current through the circuit thus formed.

In addition, the current flows through the 35 photo-electric cell to the contact —13—, which contact is movable with respect to the slide wire —14—, the current returning through the galvanometer and wire —6— to the battery —7—. Variations in the current flowing in this circuit effected by variations of resistance in the photo-electric cell will cause deflection of the galvanometer needle, but the needle will again return to its zero position when a proper adjustment 45 of the slide wire with respect to contact —13— is made, so that the currents flowing in two circuits balance each other.

The resistance —10— should be made adjustable so that if any variations in the 50 sensitivity of the photo-electric cell occur by reason of use or variations in manufacture, the resistance may be used to account for such variations.

The movement of the galvanometer effected by variations in current in the photo-electric cell circuit is utilized to control the recording mechanism. All of the actual work of operating the recording mechanism is performed by the constant speed motor 60 —15— but the extent of the work and its direction are controlled by the galvanometer.

The motor may be maintained under constant speed of rotation in any suitable way, as by the centrifugal governor —16— 65 shown, and which controls the contact

—17— forming a portion of the electric circuit of the motor. When the motor slows down, the circuit through contact —17— is closed, but such action as seen in Fig. 2 short circuits the resistance, thereby allowing greater current to flow in the motor circuit causing the motor to speed up when the reverse will take place.

The electric motor drives shaft —18—, which shaft carries a pair of cams —19— and —20—, the one —19— for periodically moving the clutch lever —21— carrying one member —22— of a clutch, the other member of which is the disk —23— mounted upon the shaft —24—. The other cam —20— periodically raises the rocker arm —25— to such an extent that the arm serves to periodically raise the needle, or pointer —26— of the galvanometer. It will be noted that when the rocker arm —25— raises the galvanometer needle, the clutch member —22— is out of contact with its co-operating disk. When the circuits of the potentiometer are balanced, the galvanometer needle is positioned, as shown in Figure 3, that is, directly beneath the space between the angle levers —27— and —28—, pivoted respectively at —29— and —30—.

Under those conditions, upward movement of the rocker arm effects no movement of the angle levers. Should, however, the galvanometer needle be deflected so as to lie beneath either one or the other of the angle levers at the time of upward movement of the rocker arm, then the angle lever under which the galvanometer needle lies will be moved about its pivot, and in turn will actuate the clutch member —22— and turn such member about its pivot.

The slide wire —14— is mounted on the same shaft as the disk —23— and may, as shown, be mounted upon the circumference of a second disk, or wheel —31—. For the purpose of returning the clutch member —22— to its normal position, thereby effecting rotation of the co-acting clutch member —23—, the shaft —18— carries a pair of cams —32— and —33—, contacting respectively with the opposite ends of the clutch member —21—, which member, after movement of the rocker arm —25—, is again brought into contact with its co-acting disk —23— and is moved from position shown in Figure 4 to that shown in Figure —3— by means of the cams —32— and —33— to the position shown in Fig. 3, thereby effecting rotation of the disk —23— a distance dependent upon the extent to which the clutch member —22— was originally unbalanced by movement of one of the lever arms —27— or —28—, and the extent of movement of the said lever arm is dependent entirely upon the amount of deflection of the galvanometer.

Therefore, the extent of movement of disk

—23— corresponds with the extent of deflection of the galvanometer needle, and as the slide wire —14— is mounted on the same shaft as disk —23—, the extent of movement 5 of the slide wire will correspond to the extent of deflection of the galvanometer needle, and will, therefore, be moved sufficiently to bring the measuring circuit into balance so that the galvanometer needle will return to 10 its balanced condition directly beneath the opening between the lever arms —27— and —28—. No further movement of disk —23— will take place until the galvanometer 15 needle is again deflected by variations in the intensity of light, to which the photo-electric cell is subjected.

The recording instrument, as the pen —34— is slidably mounted upon a stationary shaft —35— so as to move laterally across 20 the record sheet, which may be mounted in any suitable way, as upon roller —36—. The pen-carrying parts —37— are directly connected to a suitable member as violin string —38—, which transfers to the pen 25 lateral movement in direct accordance with the movement of the disk —23— and therefore, the galvanometer needle.

As shown, the violin string may be wound about the shaft —24— or around any suitable 30 disk or member rotating with said shaft so as to convey a movement of the pen in direct accordance with the movement of said shaft, as effected indirectly through the movement of the galvanometer needle.

As the pen moves across the record sheet, as shown in Figure 9, and which may be mounted upon the roll, or platen, —36— for 35 positive rotation therewith, it will trace upon said sheet a line which will be in direct accordance with the variations in light to which the photo-electric cell is exposed. The record sheet may be arranged to move at any desired pre-determined speed, as for instance three (3) inches to the hour, and may be 40 calibrated along one of its longitudinal edges in time units, as illustrated, while along its end portion it may be calibrated in light quantities as foot candles, and the sheet illustrated is adapted to be so calibrated from zero to 10,000 foot candles, as 45 shown.

From the above, it will be readily understood that the apparatus described will produce a record of the intensity of the rays of 50 light to which the photo-electric cell has been exposed during the period of time shown upon the record, which record may be calibrated in units of time and light intensity. In Figure 10 I have diagrammed a means 55 for utilizing the recording mechanism to actuate a signal relay or other device, as a switch to actuate and control a source of artificial light, etc. For this purpose, the movable carriage for the pen is provided 60 with a contact member —39— which may be

in the form of a spring, and adapted to close an electric circuit through the adjustable contact —40— and battery —41— when the pen is moved by the recording mechanism to a pre-determined position along the shaft 70 —35—. The circuit so formed may include a signaling device as —42— or a relay as —43—, or both.

For instance, the contact —40— insulated from wall —44— may be adjusted to such a 75 position that the contact —39— will come in circuit closing position when the light falling upon the photo-electric cell has become of such an intensity that artificial light should be turned on, and the closing of such a 80 circuit may be utilized through a relay to automatically turn on such artificial light, or a mere signaling device may be used to give notice when a predetermined light intensity is reached.

It will be understood that the circuit closed by movement of some part of the recording apparatus, as the pen or its carriage, may be utilized as a relay for any purpose, or merely for producing a signal, and for the 90 purpose of the claims herein, the words "Indicating device" are deemed to include a signal such as a bell, a relay, a switch, or equivalent devices.

Although I have shown and described a 95 specific apparatus capable of accomplishing the objects of my invention, I do not desire to limit myself to the particular apparatus or its details of construction or operation, as many and various changes may be made in the apparatus and the details of its construction and operation, without departing from the invention as set forth in the appended claims.

What I claim is:

1. In an apparatus of the class described, an electrical circuit containing a known but variable electromotive force, a second circuit coupled with the first circuit so that the electromotive forces of the two circuits 110 oppose each other, a light reactive resistance and a potential in said second circuit and means for varying the electromotive force of the first circuit so as to equal the electromotive force of the second circuit as the 115 latter is varied in accordance with variations in the resistance of said light reactive resistance.

2. In an apparatus of the class described, an electrical circuit containing a known but variable electromotive force, a second circuit 120 coupled with the first circuit so that the electromotive forces of the two circuits oppose each other, a light reactive resistance and a potential in said second circuit 125 means for varying the electromotive force in the first circuit so as to equal the electromotive force of the second circuit as the latter is varied in accordance with variations in the resistance of said light reactive 130

1
resistance, and means for making a line record of said variations.

3. A light recording apparatus comprising the combination with a record sheet, of 5 a galvanometer, a circuit including the galvanometer, and a light reactive resistance, means rotated a distance and in a direction dependent upon the extent and direction of deflection of the galvanometer, and means 10 actuated by said rotated means for making a record upon said sheet of the intensity of the light to which said light cell is exposed while the latter is in stationary position.

4. A light recording apparatus comprising 15 a galvanometer, a circuit including the galvanometer and a light sensitive cell, means rotating a distance and in a direction dependent upon the extent and direction of deflection of the galvanometer, and means 20 actuated by said rotated means for making a record of the intensity of the light to which said light cell is exposed.

5. A light recording apparatus comprising 25 an electrical circuit including a light sensitive cell, means in said circuit affected by the change in current flowing therein as varied by the intensity of the light to which said cell is exposed, a member rotated a distance and in a direction dependent upon 30 said affected means, and a recording device actuated by the rotated member.

6. A light recording apparatus comprising 35 an electrical circuit including a light sensitive cell and a galvanometer, mechanism actuated in accordance with the deflection of said galvanometer for producing a record of the intensity of the light to which said cell is exposed.

7. A light recording apparatus comprising 40 an electrical circuit including a galvanometer and a light sensitive cell adapted to be maintained in stationary position, mechanism actuated in accordance with the deflection of said galvanometer for produc-

ing a record of the intensity of the light 45 to which said cell is exposed when in stationary position.

8. A light recording apparatus comprising the combination with a record sheet calibrated in units of light intensity and 50 time periods, of a galvanometer, a circuit including the galvanometer and a light sensitive cell, means rotated a distance and in a direction dependent upon the extent and direction of the deflection of the galvanometer 55 and means actuated by said rotated means for making a record upon said sheet of the intensity of the light to which said light cell is exposed.

9. A light recording apparatus comprising 60 the combination with a record sheet calibrated in units of light intensity and units of time, of an electrical circuit including a light sensitive cell, means in said circuit affected by the changes in the current flowing 65 therein as varied by the intensity of the light to which said cell is exposed, a member rotated a distance and in a direction dependent upon said affected means, and a recording device actuated by the rotating 70 member for producing a record upon said sheet of the intensity of the light to which said light cell is exposed.

10. A light recording apparatus comprising 75 the combination with a record sheet calibrated in units of light intensity and units of time, of an electrical circuit, including a light sensitive cell and a galvanometer, mechanism actuated in accordance with deflections of said galvanometer for producing 80 a record upon said sheet of the intensity of the light to which said cell is exposed.

In witness whereof I have hereunto set my hand this 27th day of November, 1920.

THEODORE WILLARD CASE.

Witnesses:

EARL I. SPONABLE,
BLISS S. CUSHMAN.
